UNITED STATES PATENT OFFICE.

HARTWELL A. WILKINS, OF NEW YORK, N. Y.

DUMP-CART.

SPECIFICATION forming part of Letters Patent No. 398,562, dated February 26, 1889.

Application filed March 9, 1888. Serial No. 266,697. (No model.)

To all whom it may concern:

Be it known that I, HARTWELL A. WILKINS, of the city, county, and State of New York, have invented a new and Improved Dump-
5 Cart, of which the following is a full, clear, and exact description.

The object of this invention is to provide a simple, cheap, and durable cart which may be quickly dumped, and which, when relieved of 10 its load, may be readily returned to its normal position; and to this end the invention consists, essentially, of a cart-body rigidly mounted upon a cranked axle to which the shafts or thills are connected by hinge-joints, the 15 cart-body being held from accidental dumping by means of a tongue carried by a vertical crank-shaft, said tongue engaging a keeper that is secured to the cart-body, all as will be hereinafter more fully described, and specifically 20 pointed out in the claims.

Reference is to be had to the accompanying drawings, forming a part of this specification, in which similar figures of reference indicate corresponding parts in all the views.

25 Figure 1 is a rear view of my improved form of cart. Fig. 2 is a central longitudinal sectional view of the same, the cart-body, however, being represented as it appears when in its dumping position. Fig. 3 is a central longitudinal sectional view, the cart-body, however, being represented in its normal position. Fig. 4 is a perspective view representing the locking-tongue and its connections, and Fig. 5 is a partial plan view of the cart-body.

35 In constructing such a cart as the one illustrated in the drawings above referred to I provide a heavy cranked axle, 10, upon which there is mounted a bolster, 11, and to this bolster and axle the cart body or platform 12 is 40 connected by clips or U-bolts 13, braces 14 being preferably arranged as shown best in Figs. 2 and 3.

The tongues or thills 16 are connected by the usual foot-board, 17, the connection between 45 the foot-board and the shafts or thills being stiffened and strengthened by braces 18, which are secured to the extending ends of the foot-board and to the shafts or thills. To the under side of the thills I connect coupling-irons 19, which 50 irons are bolted to the thills and to a vertical board, 20, against which the thills abut, the

coupling-irons extending directly to the rear from beneath the board 20, to be connected with the axle or the bolster carried thereby by means of hinge-joints 21. The thill or 55 shaft rungs 22 are mounted in the usual manner, but are strengthened by plates 23, which are bolted to the board 20 and to the rungs.

A vertical shaft, 24, is mounted in bearings 25, that are carried by the board 20, and this 60 shaft is guided at its upper end by a socket, 27, that is carried by a cross-bar, 26, said cross-bar being supported by the rungs 22. To the lower end of the shaft 24 there is secured a locking-tongue, 28, which, by turning the 65 shaft 24, may be brought into engagement with a keeper, 30, that is secured to the forward end of the cart-body, the locking-tongue at this time passing through an aperture, 2, formed in the board 20. 70

The particular form of cart illustrated in the drawings is designed for the carting of cord-wood, and hence is represented with side rungs, 40; but I desire it to be understood that an ordinary form of cart-body could be employed without departing from the spirit of 75 my invention.

In operation the load is piled upon the platform or body 12, the tongue 28 at this time being in engagement with its keeper 30, and 80 the cart having been drawn to the dumping-ground, the driver, standing upon the board 17, throws the shaft 24, by grasping its crank arm or handle 41, so as move the tongue 28 from engagement with its keeper, immediately after which the draft upon the shafts or thills will act to draw the axle 10 to the position in which it is shown in Fig. 2, and as the axle is so moved the cart-body will be tilted and its load discharged; but after the discharge of the load the weight of the driver, together with that of the crank-section of the axle and the forward section of the wagon-body, will act to return the wagon-body to the position in which it is shown in Fig. 3, immediately after which the driver throws the tongue 28 into engagement with its keeper. 95

In order that the load will tend to work forward instead of backward, I mount the cart-body so that its floor or platform will incline 100 downward from the rear end, and in order that the return of the cart-body to its normal

position may be facilitated I so mount said body that the preponderance of the weight of the body will be in advance of the axle.

From the construction described it will be seen that an exceedingly cheap cart is produced, and that said cart will act rapidly and automatically to discharge its load.

Having thus fully described my invention, I claim as new and desire to secure by Letters Patent—

1. In a dump-cart, the combination of a crank-axle, a body mounted thereon at one side of the center of its length, angular draft-irons pivotally connected to the crank-axle, thills secured to the forward ends of the draft-irons, and a locking device for securing the body in its normal position, substantially as described.

2. In a dump-cart, the combination, with a crank-axle and a body secured thereto, of the thills provided with a foot-board, angular draft-irons pivoted to the axle and having their forward ends secured to the thills, and a locking-tongue adapted to engage the body to lock it in position, substantially as described.

3. In a dump-cart, the combination, with a crank-axle and a body mounted thereon and provided with a keeper, of the thills 16, provided with the foot-board 17, the angular draft-irons 19, pivoted to the crank-axle and having their forward ends secured to the thills, and the shaft 24, provided with the locking-tongue 28 on its lower end for engaging the keeper of the body, substantially as described. 35

4. In a dump-cart, the combination, with a crank-axle and a body mounted thereon and provided with a keeper, of the thills 16, the foot-board 17, the apertured board 20, the angular draft-irons 19, pivoted to the axle and secured to the board 20 and to the thills, the thill-rungs 22, and the shaft 24, journaled between the thill-rungs and provided with the locking-tongue 28, substantially as herein shown and described.

HARTWELL A. WILKINS.
